US0D1092713S

(12) **United States Design Patent** (10) **Patent No.:** **US D1,092,713 S**
McRoberts (45) **Date of Patent:** **** Sep. 9, 2025**

(54) **COMBINED CEILING FAN MOTOR
HOUSING AND LIGHT KIT**

(71) Applicant: **Hunter Fan Company**, Memphis, TN (US)

(72) Inventor: **Claire Bernice McRoberts**, Memphis, TN (US)

(73) Assignee: **Hunter Fan Company**, Memphis, TN (US)

(**) Term: **15 Years**

(21) Appl. No.: **29/828,881**

(22) Filed: **Mar. 1, 2022**

Related U.S. Application Data

(63) Continuation of application No. 29/706,306, filed on Sep. 19, 2019, now Pat. No. Des. 948,022.

(57) **CLAIM**

The ornamental design for a combined ceiling fan motor housing and light kit as shown and described.

DESCRIPTION

FIG. 1 is a top perspective view of a combined ceiling fan motor housing and light kit shown in the environment of a ceiling fan, showing my new design;

FIG. 2 is a top perspective view of the combined ceiling fan motor housing and light kit, having the ceiling fan environment removed;

FIG. 3 is a bottom perspective view thereof;

FIG. 4 is a bottom view thereof;

FIG. 5 is a top view thereof; and,

FIG. 6 is a side view thereof.

Portions of the combined ceiling fan motor housing and light kit and ceiling fan environment shown in broken lines form no part of the claimed design.

1 Claim, 6 Drawing Sheets
